UNITED STATES PATENT OFFICE.

MAXIMILIAN JURISS, OF WELLINGTON, NEW ZEALAND.

DETACHABLE HEEL.

Application filed August 18, 1921. Serial No. 493,442.

To all whom it may concern:

Be it known that I, MAXIMILIAN JURISS, a subject of the King of Great Britain and Ireland, residing at 148 Ghuznee Street, 5 Wellington, New Zealand, have invented new and useful Improvements in Detachable Heels, of which the following is a specification.

My invention relates to improvements in 10 detachable heels or heel protectors made of rubber or leather, or rubber and leather, of the type in which the protectors are removed when worn away and replaced by new ones.

According to the present invention, I utilize 15 preferably the metal studs which are moulded in the rubber protectors on the underside one at the back and the other at the side. These studs engage corresponding slots in metal plates secured to the permanent heel. The slots are wide at one end and narrow at the other end to enable the stud to enter the wide part, slide freely and be adjusted in position in the narrow end of the slot, which is placed towards the rim of 20 the heel. To prevent any movement of the stud in the slot when adjusted a button mould in the rubber protector is adapted to engage a spring dome or the like in the permanent heel. The arrangement of the 25 studs engaging the slots and the button engaging the spring dome forms a triangle the apex being the stud and slot lying vertically, and the base being the other stud and slot lying horizontally with the spring button. 30 As an alternative, plates with bayonet joints may be substituted for the slots described.

Referring to the drawings, which form part of this specification, Figures 1 and 2 are views in elevation of the heel portion of 40 a boot or shoe and the detachable heel pad or heel protector removed therefrom.

Figure 3 is a view showing the method of attaching the removable heel or protector.

Figures 4 and 5 are side views partly in section of the heel portion of a boot or shoe 45 and the detachable protector.

Figure 6 shows a detail of a modification.

The detachable heel or heel protector *a* which may be made of india-rubber, balata, 50 leather, leather substitute or a combination of any or all of such materials, is provided on its underside with a series of studs or headed pins or the like secured to said heel pad in any suitable manner. The heel portion *b* of the boot or shoe (not shown) is 55 provided with one or more recesses or slots into which the studs or pins engage. In the example illustrated in the drawings, the heel pad *a* is provided with a central stud *c* located towards the rear edge of the pad and 60 with a second stud *d* located towards the front and on one side, whilst on the opposite side at the front is fixed a stud *e* provided with a substantially spherical head *e¹*.

The heel portion *b* is provided with recesses corresponding in position with the studs *c*, *d*, *e*, on the heel pad and each of these recesses is covered by an apertured plate *f*, *f¹*, *f²*. The plate *f* is located centrally towards the rear of the heel and is 65 provided with a key-hole slot *g*, the circular portion *g¹* of which is located towards the front whilst the longitudinal portion of the slot extends rearwardly towards the rear edge of the heel. The plate *f¹* is also provided with a key hole slot *h* which lies approximate in such a position that a circle with the outer end of the slot *g* as the centre passes longitudinally through the centre thereof. The plate *f²* is provided with a circular aperture *k* and beneath said aperture is located a spring *m* of any convenient construction which co-operates with the spherical head *e¹* of the stud *e* in the manner of a press button. The heads of the studs *c* and 70 *d* are of such size as to pass freely through the circular portions of the key-hole slots but when said heads are slidden into the longitudinal portions of the slots the heads engage beneath the plate and the studs are 75 secured firmly in position.

The heel pad or protector is attached in 80 the following manner.

The head of the stud *c* at the rear of the heel pad is first passed into the circular portion *g¹* of the slot *g* in the plate *f* and is then slidden rearwardly until said stud is located at the rear end of the slot. This position is 85 shown in Figure 3. The heel pad *a* is now rotated until the head of the stud *d* is in a position to pass through the circular portion of the key hole slot *h* in the plate *f¹* and the heel pad is then rotated about the centre of the stud *c* until the stud *d* is pressed to the outer end of the longitudinal portion of the 90 slot *h*. The spherical head *e¹* of the stud *e* is now in a position in which, by pressure on the outer surface of the heel, the head of the stud may be pressed into the recess *k*, the 95 sides of the spring *m* opening out to permit 100 the stud to pass through the slot. The 105 heel pad is then rotated about the centre of the stud *c* until the stud *d* is pressed to the outer end of the longitudinal portion of the slot *h*. The spherical head *e¹* of the stud *e* is now in a position in which, by pressure on the outer surface of the heel, the head of the stud may be pressed into the recess *k*, the 110 sides of the spring *m* opening out to permit

the head to pass and closing in again to firmly grip the head and retain the same in the locked position. The heel pad or protector is now firmly secured in position and 5 will not be likely to become accidentally detached during wear of the boot or shoe.

The spring means employed to secure the stud *e* in position may be of any other convenient construction. For instance instead 10 of employing a spring of the spring-button type, I may provide a slidable strip forked at its inner ends which passes through an aperture in the front vertical face of the heel, said sliding member being provided 15 with a small head as indicated at *n* in Figures 1 and 3 which permits said member to be pulled out to release the inner forked end thereof from the head *e*¹ of the stud *e*.

As shown in Figures 1 and 3, the plates 20 *f*, *f*¹ and *f*² are secured to the base of the heel proper by screws *o*. I may however secure the plates in any other convenient manner or if desired, I may provide a single plate *p* (Fig. 6) cut to snugly fit the base 25 of the heel. This plate is provided with apertures or slots *g*, *h*, and *k* similar in shape and position to the corresponding slots and apertures in the construction shown in Figure 1, the plate being secured to the base 30 of the heel by screws or in any other appropriate manner.

The studs *c*, *d* and *e* may be secured to the detachable heel pad in any suitable manner. As shown in Figure 5, the stud *c* is provided 35 with a flange *c*¹ on its outer end and with a shank portion passing through a hole in the pad, the outer end of the shank portion being provided with a washer or plate *c*² snugly fitting in a recess *a*¹ in the outer face 40 of the heel pad. The recess *a*¹ may be filled in with cement or any other suitable material.

The studs *c*, *d* and *e* on the pad *a* may be located at slightly greater distances apart 45 than the corresponding parts of the slots *g*, *h*, and aperture *k* so that when the heel is secured in position, the bending of the pad at the centre causes its edges to press tightly into contact with the edges of the heel *b*.

50 By this arrangement the button and spring dome with studs cannot be disengaged accidentally. The studs being on plates moulded in the detachable rubber protectors or on plates secured by brads to leather protectors, 55 there are no apertures in the same to collect dirt from the roads, thereby disseminating disease. My protectors are interchangeable, thus enabling the wearer always to have level heels. This is a great advantage, as 60 uneven wear of the heel is very unsightly; and by changing once a week the life of the heels is greatly prolonged. For the first pair of detachable protectors only, a flat leather heel piece with the slot plates and 65 spring dome already attached thereto ready

for nailing to the heel of the boot, may be supplied in order to save the wearer the trouble of fixing the slot plates and spring dome separately to the permanent heel and for the purpose of aligning with the detachable protector. 70

I claim:

1. A detachable heel for footwear, comprising a heel pad provided with a series of headed studs, an apertured plate secured to 75 the flat surface of the heel proper, a series of key-hole shaped slots in said plate with which said studs have an interlocking engagement, said slots being arranged so that the studs can only be brought into interlocking engagement therewith successively, and means for securing said pad against lateral and rotary movement with respect to 80 said heel proper.

2. A detachable heel for foot wear, comprising a heel proper provided with a pair of key-hole shaped slots one of which has the longitudinal plane thereof lying in the path of a circle having the narrow end of the other slot as its centre, a pair of studs secured to the heel pad and adapted to be brought successively into interlocking engagement with said slots and co-operating fastening means on the heel proper and heel pad for preventing lateral and rotary movement of the pad with relation to the heel. 95

3. A detachable heel for footwear, comprising a heel proper, an apertured plate secured to the flat surface of said heel, a key-hole shaped slot located in a plane longitudinal of the heel, a second key-hole shaped slot located towards one side of the heel and lying within the arc of a circle with its centre at one end of the first key hole shaped slot, a socket in said plate on the opposite 100 side of said heel, a heel pad having studs mounted thereon adapted to successively engage said key-hole slots, and a spherically headed member adapted to engage said socket after the studs have been interlocked 105 with said key-hole slots.

4. A detachable heel for footwear, comprising a heel proper, an apertured plate secured to the flat outer surface of said heel, a longitudinal slot located centrally at the forward end of said plate and having an enlargement in one end thereof, a second longitudinal slot also having an enlargement at one end in said plate having its longitudinal plane located in the arc of a circle struck 115 from a point at the narrow end of said first mentioned longitudinal slot, a socket in said plate, a heel having projecting headed studs adapted to engage successively with said slots, and a spherically headed member on 120 said pad adapted to engage with said socket after said studs have been interlocked with their respective slots.

5. A detachable heel for footwear, comprising a heel pad provided with a series 130

of headed studs, an apertured plate secured to the flat outer surface of the heel proper, a series of key-hole shaped slots in said plate with which said studs are successively brought into interlocking engagement, a

5 socket in said plate and heel proper, a headed member secured to said pad and adapted to pass into said socket after the studs have been interlocked with their respective slots,

and a slidable strip in said heel proper 10 adapted to be operated to engage the headed member after the engagement thereof with said socket.

MAXIMILIAN JURISS.
